UNITED STATES PATENT OFFICE.

ROBERT JARVIE BUCHANAN, OF PITTSBURG, PENNSYLVANIA.

SASH-FASTENER.

SPECIFICATION forming part of Letters Patent No. 404,467, dated June 4, 1889.

Application filed February 21, 1889. Serial No. 300,751. (No model.)

To all whom it may concern:

Be it known that I, ROBERT JARVIE BUCHANAN, a subject of the Queen of Great Britain, residing in Pittsburg, in the county of Allegheny and State of Pennsylvania, have invented certain new and useful Improvements in Sash Locks and Holders, of which the following is a specification.

The object of my invention is to provide simple, inexpensive, and readily-manipulated devices for holding a window-sash in any desired position, and for securely locking the sash to prevent unauthorized persons from opening it.

In the accompanying drawings, illustrating my invention, Figure 1 is a front elevation of my improved sash holder and lock, showing also the rack-plate in section, with which the holder engages, and the bolt-hole for the locking-bolt. Fig. 2 is an inside view of the lock and holder, showing also the rack-plate in section. Fig. 3 is a front view of the rack-plate. Fig. 4 is an end view of the lock-frame, showing also the ends of the locking-lever and bolt. Fig. 5 is a front elevation of a surface lock and holder, showing the bell-crank lever arranged to support an upper window-sash and to lock it when closed, the rack-plate being shown in section. Fig. 6 is an inside view of same with a modified rack-plate in section. Fig. 7 is a perspective view of a surface-lock with my improvements applied. Fig. 8 is a front elevation of a modified form of rack-plate. Fig. 9 is a detail view of the bell-crank lever and its handle; Fig. 10, a detail view of the devices for locking the bell-crank lever to the lock-casing; and Fig. 11 is a view of the front plate of the lock, showing how the bell-crank lever is locked to the casing.

Referring first to the first four figures of the drawings, it will be seen that the bell-crank lever or bolt A is pivoted to the casing or frame B, at a, near its edge. In this instance I have shown a mortise-lock frame. The arm x of the bell-crank lever projects beyond the side or edge of the lock-frame, and the arm y extends downwardly, as shown, and is provided with a knob C, the shank of which projects through a curved slot c in the lock-frame, the knob C being on the outside of the frame, so as to be readily manipulated. The

slot c is formed in the arc of a circle from the axis of the bell-crank lever A as a center. The outer end of the arm x is preferably inclined or curved, as shown, and engages with the teeth d of the rack-plate D, which is secured to the window-frame. Preferably these teeth are inclined or curved, as represented, to correspond with the curvature of the end of the arm x, so as to afford an even bearing and avoid or counteract the lost motion. The tooth d² on the arm x engages with the tooth d³, formed by a notch d⁴ of rack-plate when the window is closed and is to be locked; but when this device is not used a bolt E of ordinary construction may be substituted, which is normally shot out by a spring e, as shown in Fig. 2. The bolt is provided with a knob E', the shank of which projects through a slot e' in the frame or casing B.

It will be understood that when the window-sash is down the tooth d² of the rack-plate D engages with the tooth d³ of the bell-crank lever A, or the bolt E enters the recess E² in the rack-plate D, as the case may be, and locks the sash in position, so that it cannot be raised until the bell-crank lever or bolt is withdrawn. The handle or knob E' of the bolt being on the inside of the window it can only be moved by some one on the inside, thus rendering the sash "burglar-proof." When the bolt is drawn back and the sash is elevated, it may be held at any desired elevation by means of the bell-crank lever A, the arm x of which engages with the teeth d in the rack-plate.

As will be seen, the lever A is so pivoted, and its arm y is so proportioned relatively to the arm x that the arm x is held in engagement with the rack by gravity, so that as soon as the window is raised to the desired position the arm x will immediately engage with a tooth d on the rack-plate, and will hold the sash in the position to which it is elevated. When it is desired to lower the sash, the knob C is moved along the slot c in the direction indicated by the arrow, and the arm x will be drawn into the frame or casing B out of engagement with the teeth on the rack-plate. The window-sash may then be lowered.

The rack-plate is shown as consisting of straight plane side pieces D', with the teeth countersunk and arranged between the side

pieces and the rack, and the rack is arranged between the guide-strips D^2 of the window-frame. The devices when thus arranged are of a suitable construction to support a lower window-sash when open or lock it when shut, or to support an upper window-sash at any desired elevation or to lock it when closed.

In Figs. 5 and 6 a construction similar to that shown in Figs. 1 and 2 is illustrated, except that the bell-crank lever is reversed and the slot c is in like manner reversed to accommodate the change in position of the lever A. As thus arranged my improvements are adapted to lock a lower window-sash when shut or to support it when open, and also to support an upper window-sash when in any position, and to lock it when closed. When the tooth d^3 on the arm x engages with the tooth d^2 on the rack D, secured to the window-frame, the sash cannot be lowered without withdrawing the arm x into its frame or casing, and when the tooth d^3 engages with the tooth d^2 , as indicated in Fig. 5, the window cannot be raised without withdrawing the lever therefrom.

As shown more clearly in Figs. 1 and 3, the rack which I preferably employ is provided with curved teeth d , which are joined by curved front faces d' . This construction is desirable, as before explained, to allow the arm x to move easily away from the rack or into position in the rack when in use.

In Figs. 10 and 11 I have shown devices used in connection with my improved locking devices for locking them positively to the casing or frame of the lock. As shown, the shank c^2 of the knob C extends through the arm y of the locking-lever and is provided on its outer end with a spring c^3 , which is seated in a recess c^4 in the arm y , and which also bears against the flange or washer c^5 , secured to the end of the shank c^2 .

The front plate of the casing is provided with a curved slot c , as before explained, and this slot is formed at intervals with notches or recesses c' , with which engage teeth or lugs c^6 on the shank c^2 of the knob C. When the teeth thus engage with the notches in the slot, the knob cannot be moved back and forth in line with the slot to manipulate or move the locking-lever A; but by drawing out the knob against the force of the spring c^3 the teeth will be withdrawn from the slot c and the knob, shank, and teeth may be turned so as to assume the general direction

of the slot and may be readily moved back and forth to operate the locking-lever.

It may sometimes be desirable to apply my improvements to a window-sash where it would be undesirable to cut a very large mortise for the casing which would tend to weaken the frame. When this is the case, I employ a surface frame or case, such as shown in Figs. 5, 6, and 7.

My improved sash locks and holders are especially designed for use in connection with sashes without counterbalancing-weights—such as used, for instance, in railway-cars—but some forms of the locking mechanism are not thus limited in their use.

It is obvious that the tooth d^3 on the bell-crank lever and the tooth d^2 in the rack-plate may be omitted, as the lever will support and lock a sash by reason of the engagement of the end of the arm x with the teeth on the rack-plate; but I prefer to form the lever and the rack as illustrated. It is obvious, also, that the lock may be attached to the window-frame and the rack applied to the sash.

I claim as of my own invention—

1. The combination, substantially as hereinbefore set forth, of the lock frame or casing, the bell-crank lever pivoted thereto, and having an outwardly-projecting arm x formed with an outer end curved from the axis of the lever as a center, a rack-plate having teeth curved to correspond with the curved end of the arm x , and a handle C, secured to the inwardly-projecting arm of the bell-crank lever and working in a curved slot in the lock frame or casing.

2. The combination, substantially as hereinbefore set forth, of the lock frame or casing, the bell-crank lever pivoted thereto and having an outwardly-projecting arm x and an inwardly-projecting arm y , the knob or handle C, its shank c^2 , projecting through a curved slot in the lock-casing and through the arm y of the bell-crank lever and adapted to turn therein, a spring interposed between the inner end of the shank and the bell-crank lever, and the teeth c^6 on the shank, which engage with notches c' formed in the curved slot of the lock-casing, for the purpose specified.

In testimony whereof I have hereunto subscribed my name.

ROBERT JARVIE BUCHANAN.
